UNITED STATES PATENT OFFICE.

ALFRED B. FOWLER, OF BEVERLY, MASSACHUSETTS, ASSIGNOR TO UNITED SHOE MACHINERY CORPORATION, OF PATERSON, NEW JERSEY, A CORPORATION OF NEW JERSEY.

HEEL-SCOURING MACHINE.

1,312,529.

Specification of Letters Patent. Patented Aug. 12, 1919.

Application filed January 2, 1918. Serial No. 209,919.

To all whom it may concern:

Be it known that I, ALFRED B. FOWLER, a citizen of the United States, residing at Beverly, in the county of Essex and State 5 of Massachusetts, have invented certain Improvements in Heel-Scouring Machines, of which the following description, in connection with the accompanying drawings, is a specification, like reference characters on the 10 drawings indicating like parts in the several figures.

This invention relates to machines in which the operating tool is inclosed or partially inclosed by a hood and is herein 15 illustrated as embodied in a machine for scouring the heels of boots and shoes.

The heels of boots and shoes, preparatory to being blacked, waxed and burnished, are commonly scoured by having their sides presented to cylindrical heel scouring rolls and their breasts to conical heel scouring wheels or cones. Usually two rolls and two cones having covers respectively of coarse and fine sandpaper are used. All four tools are commonly 25 mounted on a single shaft with the cones at the ends of the shaft. It is desirable that close fitting hoods be provided for these rolls in order that the dust generated by the scouring operations may be effectively removed. At the same time it is necessary that the construction be such that ready access may be had to the tools when it is desired to remove and replace the abrasive covers. The heel breast scouring cones present no considerable difficulty both by reason of the manner in which the covers are attached and by reason of the location of the cones at the ends of the shaft. The cylindrical heel scouring rolls are commonly of the split type 30 comprising sections hinged together at one side of the shaft the free ends being fastened together at the other side of the shaft by some sort of catch. In order that the operator may readily unfasten the catch, spread

45 open the sections, and remove and replace the worn cover, it is necessary that part or all of the hood be moved out of the way; but a hood so constructed that the entire structure can be moved out of the way does 50 not fit the scouring roll closely enough to have the desired efficiency.

One feature of the present invention comprises a novel sectional hood constructed and

arranged for movement of the sections toward and away from the tool. It is thus possible to close the hood about the tool and maintain it in this closed position during the scouring operation and then to open the hood to permit ready removal and replacement of the abrasive cover.

According to another feature of the invention the movable sections of the hood are connected to a manually operated member manipulation of which opens and closes the hood.

It is, of course, necessary to stop the rotation of the tool whenever the cover of the tool is being removed and replaced; a further feature of the invention comprises means manipulation of which withdraws power from the tool and opens the hood; and conveniently opposite or further manipulation of the same means applies power to the tool and closes the hood.

These and other features of the invention, including certain details of construction and combinations of parts, will be described as embodied in an illustrative machine and defined in the appended claims.

Referring now to the accompanying drawings—

Figure 1 is a front elevation of a machine in which the present invention is embodied, the sections of the hood being shown in their closed positions;

Fig. 2 is a side elevation of the machine;

Fig. 3 is a detail principally in section showing the construction of the diaphragm, the end wall 19 being shown in dotted lines in the position to which it is moved by manipulation of the treadle just before it swings back into the position shown in Fig. 4; and

Fig. 4 is an end elevation of the upper part of the machine, one of the conical heel breast scouring wheels and its hood having been removed, certain parts having been broken away and sectioned, the hood being shown in its open position.

The illustrative machine comprises a pedestal 6 having bearings in the upper part for a shaft 8 on which are mounted two cylindrical heel scouring tools and two conical heel breast scouring tools. The conical heel breast scouring tools with their hoods and mountings form no part of the present in-

vention and will not be further described. It will be noted, however, that by reason of the presence of the heel breast scouring cones, the space at the outer ends of the heel 5 scouring tools is limited and that on this account special means are required for providing access to the heel scouring tools.

Referring more particularly to Figs. 3 and 4, the tool 5 is herein shown as a heel 10 scouring wheel or roll having a removable abrasive cover 7. The dust hood which partially incloses this tool comprises a stationary rear wall 9 and end wall 11, herein shown as integral, a cover 13 pivoted to the 15 rear wall, a diaphragm 15 fast to a rod 17 which is slidable through the rear wall toward and away from the tool 5, a movable end wall 19 carried by an arm 21 which is pivotally mounted on a rod 23, and a movable front wall or piece 25 pivoted about a fixed stud 27. The rear wall 9 extends forward a short distance and abuts at 20 against the segmental rear edge of the end wall 19 when the hood is closed. This hood, which 20 is connected through the hollow pedestal of the machine with a suction fan 29, is normally closed as shown in Figs. 2 and 3, the cover 13 being down, the diaphragm 15 close to the rear of the scouring tool, the end wall 25 30 19 close to one end of the tool, and the front piece 25, which is U-shaped in cross-section, raised until its forward edge is close to the periphery of the tool and its wings 125 embrace the end walls 11 and 19. With the 35 hood thus closed, a strong, concentrated draft is applied all around the tool to carry away the dust generated by the scouring or abrading operation. At intervals it becomes necessary to remove and replace the abrasive cover 7; and at such times ready access 40 must be had to the tool. The parts of the hood are then moved to the positions shown in Fig. 4 by mechanism which will presently be described. The diaphragm 15 has the 45 same function as the one shown in my prior application Serial No. 192,502, filed Sept. 21, 1917; and the broad claims to this feature will be found in that application.

Turning now to the mechanism for operating the movable parts of the hood, the hub at the lower end of the arm 21, by which the end wall 19 is carried, is pivoted on the end of the rod 23 but held from longitudinal movement with respect to said rod. 50 Consequently when the rod is moved to the right as viewed in Fig. 1, the end wall 19 will also be moved to the right, and being then unsupported except by the rod 23 will swing backwardly under the force of gravity until arrested by the chain 31 as shown in Fig. 4. Movement of the rod 23 to the right is accomplished by depressing the left hand end, as viewed in Fig. 1, of a treadle 33 fast to the end of a rock-shaft 35, said 55 rock-shaft having fast thereon a collar 37.

An arm 39 integral with the collar is pivotally connected at 41 with the lower end of an upright rod 43 to the upper end of which is pivoted the long arm 45 of a double bell-crank lever, the short arms of which are indicated at 47 and 147. The double bell-crank lever is pivoted at 51 to a fixed stud; and a link 53 is pivoted at one end to the short arm 47 and at the other to the rod 23. When, therefore, a downward pull is exerted 70 upon the rod 43, the arm 47 is swung in a counter-clockwise direction, as viewed in Fig. 1, and the rod 23 moved to the right in its bearing 55. This moves the segmental end wall 19 to the dotted line position indicated in Fig. 3 whereupon, by its weight, it swings to the position which it occupies in Fig. 4.

The front-piece 25 and the diaphragm 15 are also moved away from the scouring tool 85 by the downward movement of the rod 43. To this end an upward extension 55 on the rod 43 passes up between the arms of a fork at one end of a lever 57, said lever being pivoted to the frame of the machine at 90 and being connected at its left-hand end by a pin and slot with an extension formed on the front piece or wall 25. The rod or extension 55 has two sets of nuts 61, 63; and between the nuts 63 and the forked end of the 95 lever 57, a coiled spring 65 is located. Fast to or integral with the lever 57 is a curved arm 67, the upper end of which is connected by a pin and slot with the rod 17 by which the diaphragm 15 is carried. It will now be 100 evident that, starting with the parts of the hood in the positions illustrated in Figs. 1, 2 and 3 depression of the treadle to pull down the rod 43 will cause the front-piece 25 the end wall 19 and the diaphragm 15 to 105 assume the positions shown in Fig. 4. The operator now has ready access to the scouring wheel 5 to remove and replace the abrasive cover 7, after which the operator pulls the end wall 19 forwardly and moves the rod 110 43 upwardly, in a manner presently to be described, to move the parts 19, 15 and 25 of the hood back into the positions which they occupy in Figs. 1, 2 and 3. The cover 115 13 is raised and lowered by hand.

Thus far only the right-hand heel scouring tool, its sectional hood and the mechanism for moving the sections have been described. The corresponding elements of the left-hand heel scouring tool are similar. No 120 detailed description of them will, therefore, be given, but reference numerals increased by 100 have been applied to them so that they may readily be identified.

When the covers of the rolls or tools are 125 being removed and replaced the shaft 8 must, of course, be at rest. The present machine is so constructed that manipulation of the treadle 33 to open the hoods disconnects the shaft 8 from its source of power. The 130

shaft 8 is driven by a belt 69 which passes around a small pulley on said shaft and around a large pulley 71 on a counter-shaft 73. Loose on one end of the counter-shaft 73 is a driving pulley 75 having a conical clutch face in one end thereof to receive a correspondingly shaped clutch member 77, said member being splined to the counter-shaft and urged into operative position by a 5 coiled spring 79. A bell-crank lever 81, pivoted to the frame at 83, has at one end the usual yoke to engage a groove on the clutch member 77 and at the other end is connected by a link 85 with an arm carried by 10 a collar 87 which is fast to the rock-shaft 35. Thus, when the shaft 35 is rocked to pull down on the rod 43 and open the hoods, the bell-crank lever 81 pulls the clutch member 77 away from the driving pulley 75, thus 15 withdrawing power from the shaft 8 and allowing that shaft to come to rest.

The treadle 33, which is fast to the rock-shaft 35, has an upstanding lug 89 which engages one side or the other of a pin 91 to 20 hold the treadle in either of the extreme angular positions to which it may be moved. The pin 91, which is carried by a collar 93 loose on the rock-shaft and is normally held 25 in the operative position shown by a coiled 30 spring 95, must be moved to the right as viewed in Fig. 2 before the angular position of the treadle 33 can be changed. To this end the stems of a pair of toe-pieces 97, 99 pass through curved slots 100, 102 in the 35 frame of the machine and are fastened to a collar 104 which is loose on the rock-shaft and contacts with the collar 93. The toe-pieces thus move in unison. With the parts 40 in the positions shown in the drawings, if it is desired to stop the machine and change the covers of the rolls, the operator pushes in on the toe-piece 97, thereby moving the end of the pin 91 out of the path of the lug 89, and then, having pushed down on the 45 adjacent end of the treadle, releases the toe-piece. The pin 91, thereupon, engages the other side of the lug 89 (the right-hand side as viewed in Fig. 1), and holds the clutch in thrown-out position and the hoods open. 50 To start the machine and close the hoods, the swinging end walls 19, 119 of the hoods are first pulled forward, and then the treadle 33 is manipulated as before except that the toe-piece 99 is used and the manipulation is 55 in the opposite direction.

The rotary member of the blower 29 is loose on the shaft 73 and has fast to it a pulley 106 driven by a belt 108 which passes around said pulley, around a double belt 60 tightening pulley 110 and around a pulley 112 fast to the shaft 73. The right-hand bearing of the shaft 73, as viewed in Fig. 1, is supported in the casing of the blower and the intake pipe 114 is fastened over an opening in the lower part of

the pedestal of the machine by bolts 116. With this construction, if the machine is to be used in a factory which is fitted with a blower system, the blower 29 with its inlet pipe 114 may be removed and replaced by a 70 standard having a bearing for the shaft 73. An inlet pipe of the blower system of the factory may then be fastened to the pedestal by the bolts 116.

Although the invention has been set forth 75 as embodied in a particular machine, it should be understood that the invention is not limited in the scope of its application to the particular machine which has been shown and described.

Having fully described my invention, what I claim as new and desire to secure by Letters Patent of the United States is:

1. A machine of the class described having, in combination, an abrading tool, a 85 hood partly inclosing the tool, said hood comprising a section movable to one side of the remainder of the hood so as to expose the end of the tool and permit ready access thereto, a treadle, and connections between 90 the treadle and the movable section such that manipulation of the treadle moves the section away from the tool.

2. A machine of the class described having, in combination, an abrading tool, a 95 hood partly inclosing the tool, said hood comprising a plurality of sections movable away from the tool to permit ready access thereto, a treadle, and connections between 100 the treadle and the sections such that manipulation of the treadle moves the sections away from the tool.

3. A machine of the class described having, in combination, an abrading tool, a 105 hood partly inclosing the tool, said hood comprising a plurality of sections movable away from the tool to permit ready access thereto, and a single means manipulation of which effects such movement.

4. A machine of the class described, having in combination, an operating tool, a 110 hood partly inclosing the tool, said hood comprising a plurality of sections, and a single member arranged to act upon plural sections to move them away from the tool.

5. A machine of the class described, having in combination, an operating tool, a 115 hood partly inclosing the tool, said hood comprising a plurality of sections, a single member, and connections between the member and the sections such that manipulation of the member moves the sections away from the tool.

6. A machine of the class described having, in combination, an abrading tool and a 125 hood partly inclosing the tool, said hood comprising a stationary end and rear wall, a movable end wall, a treadle, and means for connecting the treadle with the movable end wall.

7. A machine of the class described having, in combination, an abrading tool having a removable cover therefor, a hood partly inclosing the tool, said hood comprising a plurality of sections movable respectively away from the periphery and away from the end of the tool to permit removal and replacement of the cover, and a single means manipulation of which effects such 10 movement.

8. A machine of the class described having, in combination, an abrading tool and a hood partly inclosing the tool, said hood comprising a front wall, an end wall and a 15 diaphragm, and means for moving said walls and diaphragm away from the tool.

9. A machine of the class described having, in combination, an abrading tool and a hood partly inclosing the tool, said hood 20 comprising a front wall, an end wall and a diaphragm, means for moving said walls and diaphragm away from the tool, and a single means manipulation of which moves said walls and diaphragm away from the 25 tool.

10. A machine of the class described having, in combination, an abrading tool, a hood partially inclosing the tool, said hood being normally closed about the tool but being 30 capable of being opened to permit access to said tool and treadle controlled means for opening said hood.

11. A machine of the class described having, in combination, an abrading tool, a 35 hood partly inclosing the tool, said hood being normally closed about the tool but being capable of being opened to permit

access to the tool, means for applying power to the tool, and means to control simultaneously the application of power and open- 40 or closing the hood.

12. A machine of the class described having, in combination, an abrading tool, a hood partly inclosing the tool, said hood being normally closed about the tool but being 45 capable of being opened to permit access to the tool, means for applying power to the tool, and a single member manipulation of which withdraws power from the tool and opens the hood. 50

13. A machine of the class described, having, in combination, an abrading tool, a hood partly inclosing the tool, said hood being normally closed about the tool but being 55 capable of being opened to permit access to the tool, means for applying power to the tool, and a single member manipulation of which in one direction withdraws power from the tool and opens the hood, and in another direction applies power to 60 the member and closes the hood.

14. A machine of the class described, having in combination, an operating tool, a hood partly inclosing the tool, said hood being normally closed about the tool but being 65 capable of being opened to permit access to the tool, a clutch through which power is applied to the tool, and a member manipulation of which throws out the clutch and opens the hood. 70

In testimony whereof I have signed my name to this specification.

ALFRED B. FOWLER.
